UNITED STATES PATENT OFFICE.

WALTER A. POST, OF NEWPORT NEWS, VIRGINIA.

CAR-COUPING.

SPECIFICATION forming part of Letters Patent No. 393,660, dated November 27, 1888.

Application filed August 30, 1888. Serial No. 284,176. (No model.)

To all whom it may concern:

Be it known that I, WALTER A. POST, a citizen of the United States, and a resident of Newport News, Warwick county, Virginia, have 5 invented certain Improvements in Car Couplings, of which the following is a specification.

The object of my invention is to so construct an automatic coupling attachment that it can be readily applied to cars—to freight-cars especially—of the present type without removing the draw-head, a further object of the invention being to so construct the devices that the coupling and uncoupling of the cars may be effected from either the top or sides 15 without the necessity of passing between the cars.

In the accompanying drawings, Figure 1 is an end view of a car, showing my improved coupling attachment in position. Fig. 2 is a 20 longitudinal section showing two cars coupled, and Fig. 3 is a perspective view of the attachment removed from the car.

A is the body of the car; a a, the longitudinal stringers; B, the common draw-head or coupler, 25 and C is the bumper-block.

D is a casting, of the peculiar form shown in Fig. 3, and pivoted by means of a pivot-bolt, d, to one of the stringers or cross-braces, as shown in Fig. 2. Projecting up from the plate 30 D are two heads, E and F, these heads passing up on each side of the longitudinal stringers a a, as shown in Fig. 1, so as to be on a line with the coupling B.

The head E is slotted, and pivoted in this 35 slot is a hook, G, having a head, g, which is adapted to an enlarged opening in the head F.

The head F is slotted at f', and has an enlarged orifice, f, as shown in Fig. 3, and has an inclined face, as shown in Fig. 2, to allow 40 the coupling-hook to ride up and drop into the orifice f, thus coupling the two cars together.

It will be noticed that each plate D carries on one side a coupling-hook and on the opposite side a pocket or orifice to receive a hook, so that the cars are doubly coupled by the two 45 hooks.

The orifice f is elongated to allow for the longitudinal movement of the cars.

Pivoted to a plate, I, on the end of the car 50 is a two-armed lever, J, preferably having handles j j at each end, near the sides of the car, said lever J being pivoted at i. A link, k, connects the coupling-hook with the lever J, so that on moving the lever the coupling-hook will be raised clear of the opposite head. The other arm of the lever is attached to a link, l, which is connected to a lever, n, pivoted to a bracket, m, on the head F, the lever n carrying at its inner end a plate, n', on which 60 the head of the coupling-hook rests, so that when the lever J is moved it will pull the lever n, which, in turn, will raise the plate n', lifting the head of the hook of the opposite coupler out of engagement with the head F. By having these lifting devices on both heads, the brakeman can uncouple the cars by simply moving the lever on one car, it being unnecessary to lift the levers on both cars. 65

A rod, t, connects the lever J with a lever, K, near the top of the car, this lever being preferably made in the form of a foot-lever, so that by merely pressing the foot upon said lever the cars may be uncoupled.

It will be readily seen that my invention 75 can be applied to freight-cars having the ordinary draw-head, and also to passenger-cars having the old style couplings, without the necessity of removing these couplings.

By making the heads in one piece, I simplify 80 the construction and render the device easy of operation when in position upon the car.

I claim as my invention—

1. A plate adapted to be attached to a car and having two coupling-heads—one carrying 85 a hook and the other a socket—the said coupling-heads being adapted to fit on each side of couplings already in use, substantially as described.

2. The combination of the plate D, pivoted 90 to the car-frame and provided with two upwardly-projecting heads, one head having an inclined face and provided with a socket, substantially as described.

3. The combination of a car having a central coupling and a plate, D, secured to the car, and having two coupling-heads—one on each side of the central coupling-head—with 95

a hand-lever extending to each side of the car, a link connecting the lever to the hook of one coupling-head, and a link connecting the hand-lever to a lever carrying a plate in the opposite coupling-head, all acting in unison to couple or uncouple the car, substantially as described.

In testimony whereof I have signed my name to this specification in the presence of two subscribing witnesses.
